MULTIPLE FILAMENT LAMP

Filed Nov. 25, 1927

Inventor
Ernest Bondiek

By his Attorney
George C. Heinrichs

UNITED STATES PATENT OFFICE

ERNEST BONDIEK, OF GUTTENBERG, NEW JERSEY

MULTIPLE-FILAMENT LAMP

Application filed November 25, 1927. Serial No. 235,529.

My invention relates to improvements in incandescent electric lamps or light bulbs in which a pair of filaments or a double filament is used allowing to utilize a new filament if one is ruptured or burnt out, or a lamp which at times, when it is desirable to have a very bright light, allows to increase the intensity of the light produced by a single bulb by utilizing both filaments, and it is the principal object of my invention to produce these effects by a single manipulation of the light bulb.

Another object of my invention is the provision of a lamp of this character which is extremely simple in its construction and therefore inexpensive and which produces a great saving in material, as well as in labor.

A further object of my invention is the provision of an incandescent electric lamp which may be used for a relatively long period, which may be readily manipulated by anybody, even persons not skilled in the art, to disconnect one of the filaments from the circuit for remaining inactive while the other is active or to connect both filaments in the energized circuit if it is desired to increase the intensity of the light produced by the bulb by a simple turn of the bulb. This is particularly desirable in bulbs for electric sign boards, where it will simply be necessary if one filament is broken to turn the lamp farther into its socket to make the lamp glow again, without the necessity of exchanging the bulbs, this resulting in a great saving of labor and material.

It will be evident that by designing the lamp for heavy or high wattage, each filament may be for instance of 100 watt intensity, and thus, when both filaments are energized a 200 watt bulb will be provided. This is naturally cited as an example only, as evidently any desired and suitable watt intensity from the lowest to the highest possible may be employed.

Moreover, the two filaments may be of equal or unequal resistance according to use of the lamp for domestic or home illumination, or for instance in cars or the like, and if one of the filaments is of low resistance, the lamp may be used for night lamp service,

while it may be used for reading etc., purposes by simply cutting both filaments in through screwing the lamp base entirely into the lamp socket.

These and other objects and advantages of my invention will become more fully known as the description thereof proceeds and will then be more specifically defined in the appended claims.

In the accompanying drawing forming a material part of this disclosure:—

Fig. 1 is a side elevation of the electric light or lamp bulb constructed according to my invention, and illustrating an exterior view of the same.

Fig. 2 is a sectional view of the light bulb, part of which is broken away to illustrate its interior construction.

As illustrated, the lamp comprises a bulb 10 of any desired shape and color or transparency which is hermetically sealed in the usual manner and cemented to its base 11. The outer metallic shell or screw contact is designated 12, and is made in two parts, the upper one being separated from the lower part 13 by means of an insulated portion 14, and a similar part of insulating material 15 is provided on top of the base and shell.

The sleeve 16 is embedded in the solid end of the base and has a central opening into which movably engages a contact member 17 having a flanged lower end 18 for holding and guiding member 17 in the sleeve and for limiting its outward movement. This member is adapted to engage the central contact of a lamp socket.

The upper end of the filament 19 connected with the positive pole of a light socket, is formed into a spiral leader 20 electrically or conductively connected at its end, as at 21, and the end of the filament connected to the negative pole, designated 22 is conductively connected to the shell 12, as at 23, after being guided through the base.

A second filament 24 is connected to the filament 19 and is guided upwardly through part of the base and conductively connected to part 13 of the shell, as at 25.

It will be clear that the filaments illustrated on the drawing are intended to illus-

trate a conventional form of filament only as example, and that any desired form or shape of filament arrangement may be used in connection with a filament holder 26 which 5 may be also of any desired construction and suitable material.

The operation of my device will be perfectly clear from the above description when read on hand of the drawing and it will be 10 evident that by screwing the bulb in the usual well known manner into a lamp socket so that contact member 17 just engages the socket contact and shell 12, only is in contact with the socket walls, a circuit will be closed 15 over the socket contact through filament 19, filament 22 to shell 12, and only this filament will glow.

If this filament is ruptured, the lamp bulb need simply be turned to press member 17 20 inwardly and compress the spiral or helical leader, while shell-part 13 of the shell comes into contact with the socket wall, the circuit will be closed over filament 19, filament 24 and shell-part 13, and filament 24 will glow.

25 It will be clear that both filaments will be energized to glow, if the shell is entirely screwed into the lamp socket at the beginning, when both filaments are intact.

It is to be understood, that I have shown 30 and described as an example of the many possible ways to practically construct my lamp bulb, the preferred form thereof, and that I may make such changes in the general arrangement and in the construction of the 35 minor details, as come within the scope of the appended claims without departure from the spirit of my invention and the principles involved.

Having thus described my invention, what 40 I claim as new, and desire to secure by Letters Patent is:—

1. The combination with an electric lamp 45 provided with a plurality of filaments, of a base and its shell, said shell having separate portions insulated from each other to which certain of said filaments are connected at one end, a sleeve projecting from the said base, said sleeve having an end wall provided with a spring contact member movably held in 50 said sleeve, a flange at the inner end of said contact member for limiting the outward movement of the same, and a means connected to the other end of said filaments within said sleeve and contact member for ensuring a 55 conductive contact between said member and a lamp socket in all positions of said base and its shell in said socket.

2. The combination with an electric lamp 60 provided with two filaments, of a base and its metallic shell, said shell adapted to be screwed into a lamp socket, and having separate portions insulated from each other to which said filaments are connected at one end, a sleeve projecting from said base, said 65 sleeve having an end wall provided with a

spring contact member movably held within 70 said sleeve for vertical displacement therein, and a flange at the inner end of said contact member for limiting the outward movement of said member, and a coil formed at the end of the other of said filaments tending to press said sleeve permanently into conductive engagement with said socket.

Signed at New York, in the county of New York, and State of New York this 23rd day 75 of November, A. D. 1927.

ERNEST BONDIEK.
